UNITED STATES PATENT OFFICE.

WILLIAM B. DODDRIDGE, OF ST. LOUIS, MISSOURI, ASSIGNOR TO THE AMERICAN PNEUMATIC RAILWAY DITCHER AND GRADER COMPANY, OF GRANITE CITY, ILLINOIS.

DITCHING OR EXCAVATING MACHINE.

SPECIFICATION forming part of Letters Patent No. 633,977, dated September 26, 1899.

Application filed April 21, 1899. Serial No. 713,921. (No model.)

To all whom it may concern:

Be it known that I, WILLIAM B. DODDRIDGE, a citizen of the United States, residing at St. Louis, in the State of Missouri, have 5 invented certain new and useful Improvements in Ditching or Excavating Machines; and I do hereby declare the following to be a full, clear, and exact description of the invention, such as will enable others skilled in 10 the art to which it appertains to make and use the same.

This invention relates to ditching or excavating machines; and it consists, substantially, in the features of improvement herein- 15 after described, and more particularly pointed out in the claims.

The invention has reference more especially to that class of ditching or excavating machines employed along railways for the 20 purpose of forming ditches on either side of and substantially parallel with the tracks at equal or varying distances from the tracks within the limits of adjustment of the plow or scoop forming part of the machine.

25 The principal object of the invention is to provide means for varying the distance of the plow or scoop from the side of the car or trucks upon which the supporting-crane and other parts of the ditching-machine are mounted.

30 Other objects will also more fully herein- after appear when taken in connection with the accompanying drawings, in which—

Figure 1 represents a view in perspective of a ditching or excavating machine having 35 my improvements embodied in connection therewith; and Fig. 2 is a transverse sectional view of the traveling car and the crane-support, said view being taken in a plane substantially coincident with the swinging axis of 40 the supporting-guide for the traveler of the scoop, said guide and traveler being shown in elevation.

Preliminarily to a more detailed description 45 it may be stated that the car upon which the crane and other main parts of the ditching or excavating machine are mounted is propelled along the tracks by means of an engine or locomotive, as usual, and that, so far as the main parts themselves are concerned, they

may be of any ordinary and well-known construction and arrangement.

The means or devices constituting my improvements consist of a movable traveler or clevis from which the forward end of the ditching plow or scoop is suspended in any 55 suitable manner, while the rearward end of said scoop is suspended at the end of a cable passing over suitable guides carried by the swinging crane. The traveler is operated to be moved away from and toward the side of 60 the car, and the same is guided in its movements upon a support carried by a part of the car, the said support having a swinging movement horizontally by which to conform to the movements of the traveler during the 65 adjusting operations for altering or varying the position of the scoop. The means for adjusting the traveler in either direction relative to the side of the car operate in a direct line transverse to the car, so that no shift- 70 ing thereof is necessary beyond what is required by the simple connection between said means and the traveler.

My improved ditching-machine is exceedingly simple and easily constructed and op- 75 erated, besides being most effective for the purposes for which it is intended.

Referring to the drawings, the numeral 1 designates the car, upon the platform 2 of which is arranged the deck-plate 3, and 80 mounted or supported upon said deck-plate is the upright 4, to which is attached and supported an ordinary swinging crane 5, having the usual appurtenances employed therewith for ditching or excavating operations at 85 the side or sides of a railway-track 6. No further reference will be made to these several main parts on the car beyond what is necessary to explain my improvements, which will now be described in detail.

Fastened in a socket *a* in a suitable housing *a'* on either side of the car, substantially at the longitudinal center of the latter, is a suitable yoke or coupling-head 7, to which is pivoted, by means of a pin 8, a coupling-piece 95 9, which in turn is pivotally connected at 10 with the inner end of a beam 11, on the upper surface of which are arranged parallel track-

rails 12 for the support and guidance of a movable traveler or clevis 13. This traveler comprises suitable vertical side pieces 14, properly joined together, and between which 5 are arranged suitable grooved or flanged wheels 15 for running upon the rails 12.

Connecting with the lower part of the clevis 13 by means of a pin 16, so as to have a swinging movement horizontally, is the outer 10 end of a connecting-rod 17, which is preferably hollow, and the inner end of this rod is similarly connected by a pin 18 to the end of a piston-rod 19, the head 20 of which, as shown by dotted lines, Fig. 2, works in a 15 steam or compressed-air cylinder 20^a, preferably arranged beneath and transversely of the car, the said cylinder being provided with suitable valves (not shown) to admit compressed air or other motor fluid on either side 20 of the piston-head, so as to move the rod 18 outwardly and inwardly and to reverse the same at any time during the movement of the piston in either direction. Connecting the said traveling clevis to the forward end 25 of the ditching machine or car is a steadyng and bracing cable 21, while connecting the forward end of the plow or scoop 22 with the rear side of said clevis is a shorter cable 23. The rearward end of the scoop is connected 30 by a hook 24 to the end of a cable 25, which passes upwardly over guide-pulleys 26 and 27, supported on the crane, and extends thence down through the hollow upright 4 and between rollers or cylinders 28, preferably be- 35 neath the platform 2 of the car, and around one of which the cable is wound, so as to pay itself out and be rewound in conformity with the different movements imparted to the clevis for the purpose of varying or al- 40 tering the height and distance of the plow or scoop from the side of the car. The said plow or scoop can be of any preferred form or construction, and it may be stated at this point that a duplicate motor-cylinder 29, 45 Fig. 1, is arranged alongside the cylinder 20^a beneath the car-platform, by means of which the clevis and its support and other connections may be changed to the opposite side of the car and operated therefrom in a similar 50 manner whenever it may be desired to use the scoop or plow on that side.

Fastened to the outer end of the supporting-beam 11 is a yoke 30, to which is looped or connected one end of a cable 31 for sup- 55 porting the outer end of the beam and the other end of which is looped or fastened at 30^a to the side or edge of the deck-plate 3 or other part of the machine, the said cable being provided with a turnbuckle or other de- 60 vice 31^a for lengthening or shortening it.

It will be understood that my present improvements are not related in any manner to the ditching or excavating machine proper—that is to say, to the main parts or elements 65 of which such machines are usually constituted—and for this reason no particular description thereof has been given. It will also

be understood that in referring to the several parts which make up my present improvements—such, for instance, as the traveler and its operating mechanism, together with its swinging supporting-beam, and the cable connections, &c.—the same is done in a broad or general way, since I do not limit myself to the particular construction of any of said parts or 75 to their disposition or arrangement.

Assuming the normal position of the beam 11 to be at right angles to the longitudinal center of the car and the traveler to be at the farthest point from the side, then a right-angled triangle will be formed, of which the said beam and the side of the car form the two sides and the cable 21 the hypotenuse. If the traveler is now moved toward the car, the side of the triangle formed by the beam will 80 be reduced; but the other side of the triangle, (formed by the side of the car,) as well as the hypotenuse, will remain the same. Therefore in order to accommodate itself to the changed relation of the sides of the triangle, 85 the said beam swings backwardly upon its pivot toward the rear end 35 of the machine, and at the same time the connecting-rod 17 swings upon its pivot 18 in the same direction with the beams, sufficient play being al- 90 lowed between the end of the piston-rod 19 and the connecting-rod for this purpose.

Compressed air is supplied to either of the cylinders through pipes 50 from the air-pumps on the locomotive. (Not shown.)

Said traveling clevis can also be used in connection with other parts of the ditching-machine in the same way as the scoop is operated.

It will be seen that the line of draft upon 105 the plow or scoop is through the cables 21 and 23 and the clevis.

Having thus described the invention, what I claim, and desire to secure by Letters Patent, is—

1. The combination with a ditching-machine, of a beam extending beyond the same, and a traveling clevis having a movement back and forth on said beam substantially at right angles to the machine and means operative from the machine to move the clevis back and forth on the beam.

2. The combination with a ditching-machine, of a beam supported at one side thereof, and projecting beyond the same, a traveling clevis having a movement back and forth on said beam, and means operative from the machine for moving the clevis outward from the machine and for reversing the same.

3. The combination with a ditching-machine, of a beam supported at one side thereof, and projecting beyond the same, a traveling clevis having a movement back and forth on said beam, a motor-cylinder on the machine having a piston and rod, and a connecting-rod movably connecting said piston-rod with the clevis.

4. The combination with a ditching-machine, of a pivoted beam supported at one side

thereof, and projecting beyond the same, a traveling clevis having a movement back and forth on said beam, a motor-cylinder on the machine having a piston and rod, a connecting-rod movably connecting said rod and the clevis, and a ditching plow or scoop having connection at its front end with said clevis.

5. The combination with a ditching-machine, of a traveling clevis supporting the same at one side, means for moving said clevis outward from the machine and for reversing the same, a plow or scoop, a cable connecting the same with the clevis, a cable connecting the clevis with the forward part of the machine, and a cable connected to the rear end of the scoop and passing over guides upon the machine.

10. The combination with a ditching-machine, of a pivoted beam at one side thereof,

a cable connecting the outer end of said beam 20 with a stationary part of the machine, a traveling clevis having a movement back and forth on the beam, a motor-cylinder on the machine having a piston and rod, a movable connecting-rod between said piston-rod and 25 the clevis, a plow or scoop, a cable connecting the forward end of the same with the clevis, a cable connected to the rearward end of said scoop and passing over guides on the machine, and an additional cable connecting 30 the clevis to the forward end of the machine or car.

In testimony whereof I affix my signature in presence of two witnesses.

WILLIAM B. DODDRIDGE.
